MOP

Andrew D. Williams, Ocean Drive, S. C.

Application March 28, 1940, Serial No. 326,476

4 Claims. (Cl. 15—120)

This invention relates to an improved mop of the type provided with a wringing attachment adapted to be carried by the mop at all times.

It is an aim of this invention to provide an improved wringing attachment for mops of simple, efficient and durable construction, which may be readily applied to or removed from a mop, and which may be easily operated and which will efficiently and quickly wring the mop cloth or swab.

It is a further aim of this invention to provide a mop wringing attachment comprising a minimum of two elements, one of which has the dual function of combining with a pair of forks for removably supporting the mop cloth or swab.

Other objects and advantages of the invention will hereinafter become more fully apparent from the following description of the drawing, which illustrates a preferred embodiment thereof, and wherein:

Figure 1 is a front elevational view of the invention.

Figure 2 is a side elevational view of the same.

Figure 3 is a side elevational view showing the wringing attachment in a projected position and after it has been actuated to wring the mop cloth,

Figure 4 is an enlarged fragmentary vertical sectional view showing the means for supporting the rotatable sleeve and the means for mounting the rod containing the twisting element in the sleeve, and

Figure 5 is a vertical sectional view taken along the line 5—5 of Figure 2.

Referring more particularly to the drawing, wherein like reference characters denote like or corresponding parts throughout the different views, 10 designates generally a portion of a mop handle to the lower extremity of which is secured the fork 11 comprising the corresponding sections 12 which are removably secured at their corresponding ends to the handle 10 by the fastenings 13 and which are provided with the outwardly bowed opposite ends terminating in the inturned lugs 14, as best seen in Figure 4.

A sleeve or tube 15 is loosely journaled at its ends on the lugs 14 and is removably mounted thereby and adapted to support an endless mop cloth or swab 16. Tube 15 is provided with the aligned transverse openings 17 adapted to align with an opening 18 in the swab 16 to loosely receive the shank 19, which forms the intermediate portion of a rod designated generally 20. The lower end of the rod 20 is bent to form an oblong twisting member 21, while the opposite end is bent to form the crank 22 provided with

the arcuately shaped portion 23, in its shank, for a purpose which will hereinafter be described.

The shank 19 is curved slightly, as seen in Figure 2, so that when the twisting element 21 is in a retracted position, as seen in Figures 2 and 4, adjacent the sleeve 15 the shank 19 may be disposed along the handle 10 and releasably connected to a hook 24 adjacent its upper end so that the arcuately shaped portion 23 will fit around a portion of the handle and position the remainder of the crank 22, as seen in Figure 2. The mop cloth or swab 16 is in the form of a loop and the twisting element 22 is disposed within said loop, as seen in Figures 1 and 2, so that in its retracted position it will not affect the normal operation of the mop. To wring the mop, shank 19 is disengaged from the hook 24 and swung outwardly on the tube 15 as a pivot to project or move the twisting element 21 to the free end of the cloth 16 or to the position as seen in Figure 3. Crank 22 when in this position, as seen in Figure 3, is out of engagement with the handle 10, the sleeve 15 being preferably turned so that the shank 19 is at right angles to the handle 10 to allow the crank 22 to be freely turned to revolve the element 21 to twist the swab 16, as seen in Figure 3, for wringing.

It will thus be seen that the tube or sleeve 15, which is removably mounted by means of the ends 14 of the fork section 12, not only removably supports the swab 16 but reciprocally and rotatably mounts the rod 20 so that it can be projected for projecting the element 21 to the free end of the swab and revolved for turning the element to wring the swab, and by being rotatably mounted to pivotally mount the rod so that it can be swung to or away from the handle 10 to move it to an inoperative position or to an operative position.

Various modifications and changes in the construction and arrangement of the parts forming the invention are contemplated and can obviously be resorted to, as the drawing and description are only intended to illustrate a preferred embodiment thereof, and the right is therefore expressly reserved to make such variations and changes as fall within the spirit and scope of the invention as hereinafter defined by the appended claims.

I claim as my invention:

1. A mop comprising a handle, a fork secured to one end of said handle and provided with in-turned free ends, a tube loosely mounted on said ends and adapted to support an endless mop swab, a rod projecting through said tube and

swab and loosely mounted therein, one end of said rod being bent to provide a twisting element disposed within said swab and the opposite end of said rod being bent to form a crank to revolve said element, said rod being reciprocally mounted for projecting the twisting element to the free end of said swab for twisting and wringing the swab.

2. In a mop, a rotatably mounted cloth supporting element adapted to support an endless mop cloth, a rod projecting through and loosely disposed in said element, one end of said rod being bent to form a twisting member disposed within the cloth, the opposite end of said rod being bent to provide a crank for twisting said member when in a projected position relatively to the cloth, a handle, said element being rotatably mounted, relatively to the handle, to swing the crank away from the handle whereby it may be revolved without coming in contact therewith.

3. A wringing attachment for mops comprising a mop handle, a fork secured to an extremity thereof and provided with inturned free ends, a sleeve loosely journaled on said ends and provided with aligned transverse openings, said sleeve being adapted to mount an endless mop swab, a rod having a twisting element formed on

one end thereof and having a crank at its opposite end for revolving said twisting element, the intermediate portion or shank of said rod being loosely mounted in the openings of said sleeve to position said twisting element within said cloth, and said sleeve being rotatable on said ends for swinging said crank away from the handle for revolving the twisting element when in a projected position to wring the cloth.

4. In a wringing attachment for mops, a mop handle having a fork at one end, the free ends of said fork being turned inwardly, a sleeve rotatably mounted on said ends and provided with aligned transverse openings, an endless mop swab supported by said sleeve, and wringing means for said swab comprising a twisting element formed on one end of a rod, the opposite end of said rod being bent to form a crank, the intermediate portion or shank of said rod being slidably and rotatably mounted in said aligned openings for projecting and retracting said twisting element relatively to the interior of said swab, said rod being pivotally mounted by said sleeve for swinging the crank out of engagement with the handle for devolving the twisting element, when in a projected position, for wringing said swab.

ANDREW D. WILLIAMS.
